UNITED STATES PATENT OFFICE.

JOSEPH W. KAOUGH, OF DALLAS, TEXAS, ASSIGNOR TO THE GUIBERSON CORPORATION, OF DALLAS, TEXAS, A CORPORATION OF DELAWARE.

WRENCH.

Application filed November 8, 1923. Serial No. 673,610.

To all whom it may concern:

Be it known that I, JOSEPH W. KAOUGH, citizen of the United States of America, residing at Dallas, in the county of Dallas and 5 State of Texas, have invented certain new and useful Improvements in Wrenches, of which the following is a specification.

This invention relates to new and useful improvements in wrenches.

10 The invention has particularly to do with that type of wrench which is designed for use on pipes, well casing and tool joints or other cylindrical objects which are used in a perpendicular position.

15 An object of the invention is to provide in combination with a gripping jaw, a pair of clamping jaws having self closing fingers and a self-acting latch, whereby the clamping jaws swing through a shorter radius 20 and are more readily opened and closed.

Another object of the invention is to provide shoes for the jaws together with novel 25 means for fastening them to the jaws, whereby pipes of smaller diameters may be gripped.

A particular object of the invention is to provide in combination with its shoes, detachable jaw closing fingers which permit 30 of a proper location of the fingers with respect to the shoes or jaws.

A further object is to provide a self-engaging latch for the free ends of the clamping jaws together with an inter-meshing arrangement, whereby the free ends of the 35 jaws are prevented from sagging when clamped in a horizontal plane about a pipe.

A very important object is to provide a wrench of the self-acting jaw type which will be readily adjustable to various pipe 40 sizes, particularly small diameters.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a plan view of a wrench constructed in accordance with my invention,

Fig. 2 is a side elevation of the same,

Fig. 3 is a sectional view on the line 3—3 of Fig. 1,

Fig. 4 is an enlarged plan view of the 55 head and jaws of the wrench, and

Fig. 5 is a view of the opposite side from Fig. 2.

In the drawings the numeral 10 designates a head having cheek plates 11 connected at one side by a web 12 and at the other side 60 by a web 13, thus providing a space between the plates extending longitudinally through the head. The head has a concaved seat 14 at its forward portion. A lug 15 is formed on the extreme left hand end of the head, (Fig. 5), while inwardly offset ears 16 (Fig. 2) are provided on the extreme right hand end of the head.

A gripping jaw 17 has a reduced ear 18 fitting between the ears 16 as is shown in 70 Fig. 2. A bolt 19 passing through the ears 16 and 18 acts as a pivot for the jaw. The jaw has a flange 17' conforming to the seat and substantially flush with the cheek plates. A coiled spring 20 secured in the head is 75 attached to the free end of the jaw 17 and tends to hold the flange 17' seated.

A pair of clamping jaws 21 and 22, respectively, are mounted on the head. The jaw 21 has ears 23 counter-sunk in the ears 80 16 and mounted on the bolt 19, so as to be substantially flush with the cheek plates. The jaw 22 has ears 24 engaging on a bolt 19' passing through the lug 15. The free end of the jaw 22 has a converging socket 85 25 which receives the reduced and beveled end 26' of the jaw 21 at the center of the wrench, whereby sagging of the jaws is prevented. The jaw 21 has a hook latch 26 on its reduced end which engages in a keeper 90 27. The keeper is pivoted on the free end of the jaw 22. A yoke spring 28 has one end straddling the latching-end of the keeper and its inner end embracing the jaw 22, while the sides of the spring are coiled 95 about the pivot of the keeper. The ends of the hook and keeper are sufficiently rounded to cause an easy self-latching action when the clamping jaws are swung together.

An important feature resides in removable jaw closing fingers 29 and 30, respectively, arranged in pairs straddling the cheek plates. The fingers 29 are fastened to the ears 23 of the jaw 21 by screws 31 and each finger has a laterally extending lug 29' 100 engaging over the back or outer edge of the jaw 21, so that pressure against the fingers is also sustained by said lugs. The fingers 30 are fastened to the ears 24 by screws 31' 105 and have lugs 30' engaging over the outer 110

edge of the jaw 22. The jaws 21 and 22 have stops 21' and 22', respectively on their ears, which engage the head and limit the outward swing of said jaws.

5 This type of wrench lends itself readily to numerous adjustments, whereby a wide range of pipe sizes may be engaged. A curved shoe 32 may be fastened to the face of the flange 17' for reducing the inner diameter of the jaws. It is possible to use various means for fastening shoes to the jaws, and I have shown the shoe 32 fastened with a machine bolt 33, while for smaller diameters a shoe 34 is fastened to the jaw 21 and a shoe 35 is secured to the jaw 22. The shoe 34 is shown provided with lips 36 overlapping the jaw 21 and fastened by machine bolts 37, while the shoe 35 is fastened by a machine bolt 38 inserted through the jaw 22, instead of being countersunk as is the bolt 33. Any desired fastening may be selected.

It will be noted that the fingers 29 and 30 are set so as to project inwardly of the jaws 21 and 22 and co-act with the faces of the shoes. This is necessary in order that the clamping shoes may be fully closed by the engagement of the pipe with the fingers. The fingers being detachable may be removed. Thus 30 when a larger size of pipe was to be worked upon one of the shoes would be removed and the fingers would have to be positioned accordingly. Another set of fingers for this purpose could be readily substituted and the user would not be required to purchase a larger size or a smaller size wrench under usual conditions.

In case a finger is broken or battered it 40 might be replaced. In some instances it might be desired to close the jaw 22 by hand and therefore the fingers 30 could be omitted. The detachable fingers offer a very flexible arrangement and while I have shown them secured with screws and provided with 45 sustaining lugs, they could be otherwise attached and formed.

The gripping jaw 17 has an inner curved face 39 in position to be engaged by a displacing member 40 on the inner end of a handle 42 mounted on a pin 41 secured in the head. The member 40 is sufficiently broad to displace the jaw 17 from the seat 14 and into gripping position when the handle is swung. While I have shown the handle 42 and the member 40, it is to be understood that any means may be used for displacing the jaw 17.

It is desirable to hold the handle 42 against swinging and the head in a central 60 position and while any suitable means may be used for this purpose, I have found a spring latch bolt to give satisfactory results. On the handle is mounted a housing 44 in which a pair of headed bolts 45 are mounted 65 to slide.

The cheek plate on this side has a stud 46 on its inner end relatively between the bolts. Each bolt has a coiled compression spring 47 confined thereon and bearing against the housing and tending to withdraw the bolts 70 from the path of the stud. An abutment plate 48 is fastened on the handle 42. Each bolt 45 has a hand hook 49 and by grasping either of these, the bolt thereof may be displaced against the tension of its spring 47 75 and caught against the edge of the plate 48, whereby the head of the bolt will be held in the path of the stud. By displacing both bolts the head 10 and the handle will be engaged for unitary movement. When only 80 one of the bolts is displaced the handle is free to swing independently in one direction only. As is shown in Fig. 1 the right hand bolt 45 is displaced and when the handle is swung to the left the head will also 85 be swung therewith, but when the handle is swung to the right the head 10 will remain (relatively) stationary and the member 40 will fulcrum on its pin 41, forcing the jaw 17 into action.

In using the wrench the clamping jaws 21 and 22 are swung open as is shown in full lines in Fig. 4. The head 10 is moved toward the pipe which is engaged by the fingers 29 and 30, which latter were swung into its path when the jaws were opened. As the movement of the head toward the pipe is continued the fingers are displaced, whereby the jaws 21 and 22 are swung in behind the pipe until the hook 26 engages in the keeper 27 and the clamping jaws are thus fastened as is shown in dotted lines in Fig. 4 and in full lines in Fig. 1.

The bolts 45 are both engaged with the lug 46 during the jaw-closing movement, 105 but in order to swing the member 40 and displace the jaw 17 to grip the pipe, one of the bolts 45 must be retracted, according to the direction in which it is necessary to swing the handle 42. When the handle is released 110 it may be swung and the pipe firmly gripped.

It is obvious that other latching means could be used and various other changes, modifications and alterations may be made within the scope of the appended claims. 115

What I claim, is:

1. In a wrench, a head having a seat, a gripping jaw pivoted in the head, means for displacing the gripping jaw into gripping position, a pair of clamping jaws hinged to the head and co-acting with the gripping jaw, and jaw closing fingers detachably connected with one of the clamping jaws. 120

2. In a wrench, a head having a seat, a gripping jaw pivoted in the head, means for displacing the gripping jaw into gripping position, a pair of clamping jaws hinged to the head and co-acting with the gripping jaw, jaw closing fingers detachably connected with one of the clamping jaws, and means 125 130

for fastening the free ends of the clamping jaws together.

3. In a wrench, a head having a seat, a gripping jaw pivoted in the head, means for displacing the gripping jaw into gripping position, a pair of clamping jaws hinged to the head and co-acting with the gripping jaw, jaw closing fingers detachably connected with one of the clamping jaws, and means for fastening the free ends of the clamping jaws together, one of the clamping jaws having a socket on its free end for receiving the free end of the other clamping jaw.
4. In a wrench, a head having a seat, a gripping jaw pivoted in the head, means for displacing the gripping jaw into gripping position, a pair of clamping jaws hinged to the head and co-acting with the gripping jaw, and jaw closing fingers on both clamping jaws detachably attached thereto.

5. In a wrench, a head having a seat, a gripping jaw pivoted in the head, means for displacing the gripping jaw into gripping position, a pair of clamping jaws hinged to the head and co-acting with the gripping jaw, jaw closing fingers on both clamping jaws detachably attached thereto, and a self-latching keeper carried by one of the clamping jaws and engaged by the other clamping jaw.

6. In a wrench, the combination of a head having a seat, a gripping jaw pivoted in the head and swinging through said seat, a curved shoe detachably mounted on said gripping jaw, a pair of clamping jaws piv-

oted to the head and co-acting with the shoe to grip an article, means for fastening the clamping jaws together, jaw closing fingers detachably mounted on the pivoted ends of the clamping jaws, and means for actuating the gripping jaw.

7. In a wrench, the combination of a head having a seat, a gripping jaw pivoted in the head and swinging through said seat, a curved shoe detachably mounted on said gripping jaw, a pair of clamping jaws pivoted to the head and co-acting with the shoe to grip an article, means for fastening the clamping jaws together, jaw closing fingers detachably mounted on the pivoted ends of the clamping jaws, means for actuating the gripping jaw, and additional curved shoes detachably mounted on the inner faces of the clamping jaws.

8. In a wrench, the combination of a head having a seat, a gripping jaw pivoted in the head and swinging through said seat, a curved shoe mounted on said gripping jaw, a pair of clamping jaws pivoted on said head, additional curved shoes mounted on the clamping jaws, jaw closing fingers detachably mounted on the pivoted ends of the clamping jaws and co-acting with the shoes, means for connecting the free ends of the clamping jaws, and means including a handle for displacing the gripping jaw into gripping position.

In testimony whereof I affix my signature.

JOSEPH W. KAOUGH.
